DESIGN FOR A BOTTLE OR SIMILAR ARTICLE

Harris Whitaker, Bloomfield, N. J., assignor to Bourjois, Inc., New York, N. Y., a corporation of New York

Application February 21, 1938, Serial No. 75,309

Term of patent 14 years

To all whom it may concern:

Be it known that I, Harris Whitaker, a citizen of the United States of America, residing at 182 Ashland Avenue, Bloomfield, in the county of Essex and State of New Jersey, have invented a new, original, and ornamental Design for a Bottle or Similar Article, of which the following is a specification, reference being had to the accompanying drawing, forming a part thereof, and showing in Fig. 1 a front view, in Fig. 2 a side view and in Fig. 3 a top view of a bottle embodying my design.

I claim:

The ornamental design for a bottle or similar article, substantially as shown.

HARRIS WHITAKER.
